TAKE-UP FOR FOURDRINIER MACHINES

Filed Dec. 12, 1931

UNITED STATES PATENT OFFICE

JOSEPH A. WHITE, OF MELROSE PARK, PENNSYLVANIA, ASSIGNOR TO THE MOORE & WHITE COMPANY, OF PHILADELPHIA, PENNSYLVANIA, A CORPORATION OF PENNSYLVANIA

TAKE-UP FOR FOURDRINIER MACHINES

Application filed December 12, 1931. Serial No. 580,711.

My invention relates to certain improvements in Fourdrinier paper-making machines.

One object of my invention is to provide means for taking up considerable slack of the making wire of the machine so that when the wire is slack it can be readily removed laterally from the machine and it is desired to replace the wire with a new wire, which can be also placed in position, and the slack of the wire can be taken up sufficiently to make the wire taut.

A further object of the invention is to provide two take-up mechanisms, one actuated from a single operating means.

A still further object is to so design the take-up mechanism that one of the take-up rolls will balance the other take-up roll.

The making wire of a Fourdrinier paper-making machine must be replaced at frequent intervals by new wire. These wires are endless and it has been the usual practice to adjust the breast roll or remove the roll entirely so as to allow enough slack in the wire that it can be readily removed and a new wire placed in position. This is a very delicate operation as the least little imperfection in the wire makes it useless in making paper, especially high grade papers.

By my invention the rolls over which the wire passes are not adjusted or removed, and the slack of the wire is taken up by mechanism located under the machine and which bears upon the return run of the wire.

In the accompanying drawing:

Fig. 1 is a side view of a paper-making machine, illustrating my invention;

Fig. 2 is an enlarged view of part of Fig. 1, with the slack take-up mechanism in position when the wire is tightened and ready for the making of paper; and

Fig. 3 is a view similar to Fig. 2, showing the slack take-up mechanism in position to allow considerable slack in the wire, so that the wire can be readily removed from the machine without removing the breast rolls or other parts of the machine.

1 are standards which support the frames 2 and 3 of the Fourdrinier machine. The machine is divided into two sections, the first

section 4 being the paper-forming section and the section 5 being the suction box section for removing surplus water from the formed paper. 6 is a series of rollers which support the wire 7, while the paper is being formed. 8 is the breast roll at the forward end of the machine and 9 is the couch roll around which the wire passes after leaving the suction boxes. 10, 11 and 12 are guide rolls for the return run of the wire. The guide rolls 11 and 12 are mounted in bearings depending from the frame 2, while the guide roll 10 is supported on suitable bearings mounted on the floor. 13 is the take-up of the ordinary type mounted on arms 14 which are raised and lowered by a shaft 15 geared to the arms and provided with a hand-wheel.

16 and 17 are the take-up rolls forming part of my present invention. The roll 17 is mounted in bearings 18 on arms 19 carried by a shaft 20 mounted in bearings 21, and secured to the shaft is an arm 22 connected by a rod 23 to an arm 24 on a shaft 25. Secured to the shaft 25 are arms 26 carrying bearings 27 for the roll 16. The two rolls are very heavy and by the construction described above the one roll balances the other, so that it takes comparatively little power to shift the rolls to take up the wire or to slacken it. The arms 22 and 24 and the connecting rod 23 are at the back of the machine.

On the shaft 25 is a toothed segment 28, which meshes with the pinion 29 on a shaft 30. On this shaft is a worm-wheel 31, with which meshes a worm 32 on a longitudinal operating shaft 33 mounted in suitable bearings on the frame 3 at the back of the machine. At the opposite end of the shaft is a beveled gear-wheel 34, which meshes with a beveled gear-wheel 35 on a transverse operating shaft 36, on which is a hand-wheel 37 at the front end of the machine.

By the above construction, when the roll 16 is raised to slacken the wire, the roll 17 is lowered to increase the slack in the wire as shown in Fig. 3, and when the roll 16 is lowered to place tension on the wire, then the roll 17 is raised for the same purpose. The two rolls are operated simultaneously in opposite directions on turning the hand-wheel 37 of

the operating shaft 36, the motion being imparted through the shaft 33 and worm-wheels, pinion 29 and segment 28. The take-up roll 13 can be lowered when it is desired to place additional slack in the wire and can be raised until the desired amount of tension is secured. My improved apparatus is very simple and is quickly operated and provides sufficient slack in the wire to allow the wire to be readily removed from the machine and 10 a new wire placed in position.

I claim:

1. The combination in a Fourdrinier paper making machine, of a making wire; means for guiding the wire through the machine; 15 two take-up rolls arranged to move in opposite directions for either taking up the slack or providing slack in the making wire and means for operating the two take-up rolls in unison.
2. The combination in a Fourdrinier machine, of a paper-forming section; a suction box section; a roll at either end of the machine; a making wire arranged to pass around the two rolls and over the forming section 25 and the suction boxes; two take-up rolls arranged to move in opposite directions for either taking up the slack or providing slack in the making wire; and means for operating the two rolls in unison.
3. The combination in a Fourdrinier machine, of a making wire; means for supporting the wire in the machine; two take-up rolls; two shafts; arms on each shaft on which said take-up rolls are mounted, each shaft having a second arm and a rod connecting the two last-mentioned arms; an operating shaft having a hand-wheel; and gearing between the hand-wheel and one of the first- 35 mentioned shafts, so that on turning the hand-wheel in one direction the one take-up roll will be raised and the other lowered, and when the hand-wheel is turned in the opposite direction the movement of the rolls will 40 be reversed.
4. The combination in a Fourdrinier machine, of an endless making wire; means for guiding the wire through the machine; two transverse shafts; arms on each shaft; a take-up roll carried by the arms of each shaft; a short arm on each shaft; a rod connecting the two short arms; bearings for said shafts; a toothed segment on one of said shafts; a pinion meshing with the segment; a shaft on 50 which the pinion is mounted; a worm-wheel on said shaft; a worm meshing with the worm-wheel; a longitudinal shaft on which the worm is mounted; an operating shaft; beveled gearing between the operating shaft 55 and the longitudinal shaft; and means for turning the operating shaft so that when one roll is lowered the other roll is raised to take up the slack in the wire, and when the movement of the operating shaft is reversed the 60 first-mentioned roll is raised and the other 65

roll lowered to allow the wire to become slack.

5. The combination in a Fourdrinier paper-making machine, of a making wire; means for guiding the wire through the machine; two take-up rolls located under the machine and arranged to take up the slack on the return run of the wire; two transverse shafts spaced apart; two arms on each shaft, one of said rolls being mounted on one pair of said arms, the other roll being mounted 75 on the other pair of said arms; an arm on each shaft at the back of the machine; a rod connecting the two last-mentioned arms; a transverse operating shaft having a hand-wheel at the front side of the machine; and so means connecting the said operating shaft to one of said transverse shafts, said means being located at the rear side of the machine, so that when the operating shaft is turned in one direction the rolls will be actuated in 85 unison to take up the slack of the wire and when the shaft is turned in the opposite direction the rolls will be moved so that sufficient slack will be provided in the wire to allow it to be removed from the machine. 90
